INVENTOR
BY Victor J. Evans
ATTORNEY

UNITED STATES PATENT OFFICE

MORRIS OWEN, OF OAK PARK, ILLINOIS

FURNACE ATTACHMENT

Application filed June 4, 1928. Serial No. 282,734.

This invention relates to certain novel improvements in furnace attachments, and has for its principal object the provision of an improved construction of this character which will be highly efficient in use and economical in manufacture.

It is among the objects of my invention to provide a device which may be associated with furnaces or the like so as to increase the combustion efficiency in the fire boxes thereof and this is accomplished by collecting in a suitable manner the gases passing through the flue, and directing them back into the fire box above the fire therein.

Another object of the invention is to provide a device of the above named type which may be associated with the door of the fire box, and which will be mounted so as to extend over the fire box above a fire bed therein, in order that gases passing therethrough may be heated prior to their admittance into the fire box.

Another object of the invention is to arrange the device mounted in the fire door and the pipe leading from the flue in such a manner that the door may be opened without causing the attachments to interfere.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a fragmental vertical section of a view depicting my improved device in association with the door of a fire box.

Fig. 2 is a sectional view taken substantially on the line 2—2 on Fig. 1; and

Fig. 3 is an elevational view looking in at the right-hand end of the device as illustrated in Fig. 1, the delivery spout having been removed.

In the drawing wherein the preferred embodiment of my invention is illustrated 10 indicates a fire door of any approved type which is adapted to be associated with the fire box of a furnace of any desired construction, and an opening 11 is provided in this fire

door preferably centrally thereof. On the inner side of the fire door 10 a sleeve 12 is mounted which includes an inner opening that is adapted to be aligned with the opening 11 in the fire door 10, and the sleeve 12 includes a flange 13 that is adapted to abut the inner surface of the door 10. A ring 14 is mounted on the outer side of the fire door 10 in alignment with the flange 13 and aligned openings are provided in the ring 14, 55 the fire door 10, and the flange 13 through which bolt members 15 are extended, and which are engaged by nut members 16 so as to lock the flange 13 and the ring 14 in engagement with the fire door 10. 60

A substantially cylindrical member 17 is mounted in the sleeve 12 and is arranged such that one end thereof extends beyond and outwardly of the fire door 10 as clearly illustrated in Fig. 1. This cylindrical member 17 includes an end wall 18 that is adapted to close one end of the circular member 17 with the exception of the upper portion thereof and arranged in alignment with the upper end of the end wall 18 and spaced from the upper portion of the member 17 is a partition 19 which extends axially of the member 17 and which ends in spaced relation with the end wall 20 of the member 17 which is arranged opposite the end wall 18. The end 70 wall 20 closes the end of member 17 with the exception of the portion adjacent to the lower end thereof and at this end of the member 20 a partition 21 is provided which extends inwardly and axially of the member 17 in 75 parallel relation with the partition 19, and the partition 21 is arranged in spaced relation with respect to the end wall 18 and the partition 19. Thus passages 22, 23, and 24 are provided in the member 17. The upper 80 end of the wall 18 ends as has been stated in spaced relation with respect to the upper side of the member 17 and, therefore, an inlet opening 25 provided, which is in communication with the passage 23. The passage 22 is in communication with the passage 23 through 85 the space provided by the ending of the partition 19 in spaced relation with respect to the wall 20. The passage 24 is in communication with the passage 23 through 90

the partition 21 in spaced relation with respect to the wall 20. The passage 24 is in communication with the passage 23 through 95 100

the opening provided by the ending of the partition 21 and in spaced relation with respect to the end wall 18 and the foreshortening of the wall 20 in the manner set forth 5 provides an outlet opening 26 which is obviously in communication with the passage 24.

Arranged on the outer side of the wall 20 are two guide members 27 and 28 which are 10 adapted to open inwardly toward each other in order that flanges provided on the discharge spout 29 may be removably mounted therein and obviously this discharge spout is in communication with the discharge opening 26. It is apparent that it will be desirable to extend the construction over fire boxes in varied amounts and therefore by inserting discharge spouts 29 of different lengths, the length of the device may be varied.

Secured to the ring 14 on the inner side 20 thereof is one end of an elbow construction 30. The opposite end of this elbow construction 30 opens upwardly as clearly indicated in Fig. 1. Mounted, so as to be slidably 25 received by this upwardly directed end of the elbow construction 30, is the end portion 31 of the mixing chamber 32. The mixing chamber 32 includes an inlet opening 33 of relatively large diameter. The discharge portion 34 of a supply pipe is connected 30 to the supply pipe 36. The supply pipe 36 is adapted to be directed to a suitable gas collector located in the flue in the manner set forth in my copending application entitled Gas circulator, filed 35 in the United States Patent Office on or about May 6, 1927, and which bears the Serial No. 189,395. As is apparent by referring to Fig. 1, the size of the pipe 34 is relatively small when compared to the size of 40 the opening 33 and it is therefore apparent that the fire door 10 may be moved an appreciable distance before the pipe 34 engages one of the walls of the chamber 32. It is 45 also apparent that since the space around the pipe 34 is great, a suitable amount of fresh air will enter the chamber 32 and will be mixed with the gases emitted from the pipe 34 and therefore this fresh air and the 50 gases mixed in the chamber 32 will pass downwardly through the elbow construction 30 to the inlet opening 25.

A portion of the member 17 extends above 55 the fire in the fire box with which the door 10 is associated. It is therefore apparent that this member 17 will become heated and therefore the gases passing through the opening 25, passage 22, passage 23, and passage 24, will be heated before passing through the 60 discharge opening 26 and the discharge spout 29, and therefore the gases passing from the discharge spout 29 so as to be disbursed over the fire in the fire box will be heated to a relatively high temperature and therefore combustion efficiency will be increased.

It is apparent in the foregoing description that I have provided a device which may be expeditiously mounted in association with the fire door and it is also apparent that the device will be arranged so as not to interfere 70 with the opening and closing of the fire door. In addition to the foregoing, the device is arranged such that it may be extended into the fire box in varying amounts, in order that the discharge will be at the point best 75 suited for the efficient combustion.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variation and modifications as come within the scope of the 80 appended claim.

Having thus described my invention what I claim as new and desire to protect by Letters Patent is:

In combination with a door of a fire box 90 having an opening therein, a member secured to the inner wall of said door including an annular flanged portion disposed around said opening, said member including a portion protruding substantially right angularly 95 therefrom, said protruding portion being aligned with the opening in said door and providing a sleeve, a cylindrical member disposed in said sleeve portion and extending through said opening in said door, means for securing said cylindrical member in said sleeve, said cylindrical member having partially closed end portions providing oppositely disposed openings in the ends of said member, said end portions having portions integral therewith providing shelves extending inwardly from said end portions and extending longitudinally through said cylindrical member whereby a tortuous passage is provided through said cylindrical member, a discharge spout arranged over the opening in the rear end portion of said cylindrical member, a ring secured to the outer face of said fire door, means connected to said ring providing a passage communicating with the tortuous passage in said cylindrical member and communicating with said discharge spout through said tortuous passage, an elbow structure retained by said ring portion, a housing mounted on the upper end of said elbow structure, said housing having an opening provided in one wall thereof, and a pipe member extended through said last named opening and projecting upwardly from said housing structure.

In testimony whereof I affix my signature.
MORRIS OWEN.
